ATTY.

UNITED STATES PATENT OFFICE

169,369

HOUSING FOR A MICROFILM READER
OR THE LIKEClyde L. Forrester, Chicago, Ill., assignor to Bell
& Howell Company, Chicago, Ill., a corporation
of Illinois

Application January 7, 1953, Serial No. 23,072

Term of patent 14 years

(Cl. D61—1)

To all whom it may concern:

Be it known that I, Clyde L. Forrester, a citizen of the United States, residing at Chicago, State of Illinois, have invented a new, original, and ornamental Design for a Housing for a Microfilm Reader or the like, of which the following is a specification, reference being had to the accompanying drawing, forming a part hereof.

In the said drawing—

Figure 1 is a front perspective view of a housing for a microfilm reader or the like, embodying my new design, and

Figure 2 is a rear perspective view thereof.

I claim.

The ornamental design for a housing for a microfilm reader or the like, as shown.

CLYDE L. FORRESTER.
